3 Claims. (Cl. 128—295)

This invention relates to a device or apparatus for the confining, collection and removal of urine discharged by an invalid or an infant. This invention is concerned particularly with an apparatus having a collector bag that can be sealingly applied to the crotch portion of the human body by means of a suction action that also acts to collect and withdraw the fluid resulting from an act of urination or the like.

It is a primary object of this invention to provide an apparatus including a collector bag that may be applied to the crotch portion of the human body and sealingly retained in position by sub-atmospheric internal pressure such that any fluid discharged into the bag will be trapped within the bag and readily removed therefrom by means of the suction source producing the sub-atmospheric pressure within the bag.

It is still another object of this invention to provide a urination control device that is easily applied to and comfortably retain in position on the crotch portion of a human being such that the user has freedom of movement and can enjoy uninterrupted rest while using this device.

It is a further object of this invention to provide a urination control device having a pants-like collector bag to be worn on the crotch portion of the human body with said collector bag being readily connectible to any common type of sub-atmospheric pressure source such that the subatmospheric pressure within the bag will produce a liquid tight seal between the bag and the surrounding body portion and also cause withdrawal of any fluid discharged into the bag.

It is still another object of this invention to provide a device for persons experiencing urination control problems wherein a pressure differential is utilized to effect a leakproof seal and to drain away any fluid that may be emitted.

Other objects and advantages of this invention will become readily apparent from a reading of the following description and a consideration of the related drawings wherein:

Fig. 1 is an elevational view, partly in section of one embodiment of this invention;

Fig. 2 is an enlarged front elevational view of the collector bag utilized with the invention shown in Fig. 1;

Fig. 3 is a side elevational view of the collector bag shown in Fig. 2;

Fig. 4 is a sectional elevational view taken along the line 4—4 of Fig. 3;

Fig. 5 is a fragmentary sectional elevational view taken along the line 5—5 of Fig. 4; and

Fig. 6 is an elevational view of another form of this invention.

It is common knowledge among those who care for the sick and the very young that accidental or uncontrollable acts of urination are very annoying to all parties concerned and furthermore, these acts produce objectionable bed conditions that disturb the patient or infant and prevent

the attainment of the maximum amount of rest and the benefits associated therewith. This invention relates to a device in the nature of an undergarment that may be readily applied to and worn on the crotch portion of the human body without any discomfort whatever and which device will entrap and drain away the results of any act of urination or the like without causing any soiling of the patient's bed garments or the bedding on which the patient is resting. This undergarment portion of this device is similar to a pair of underpants and it is made of some waterproof fabric that preferably is somewhat elastic so that it has a tendency to fit closely about the crotch portion of the person to which it is applied. This flexible waterproof undergarment functions as a collector bag to entrap any urine that might be emitted by a patient or infant and because it is connected by a conduit to a suction source the urine will be drained away and deposited in an accumulator jar, tank or the like. Thus the urine will not be in contact with the exterior skin surfaces of the crotch portion for any appreciable time whatever. This tends to prevent the development of skin irritations that sometimes result from the contact between urine and the external skin around the crotch portion. Also, because the urine is immediately drained away after its emission there is little chance for any leakage to develop or for any odors to develop.

The immediate removal of the urine from the collector bag after its collection prevents any uncomfortableness that might result from having the bag swell due to liquid filling the bag interior.

This invention involves the use of a physical principle in a specific manner that is thought to be new and novel as applied to devices of this general type. It is a well-known principle that liquid will not, in and of itself, flow up hill. Likewise, liquid cannot freely flow from a low pressure chamber to a high pressure chamber. Accordingly, if liquid is collected in a collector bag, or the like, wherein the internal pressure is sub-atmospheric, then the collected liquid cannot flow or leak out of the bag to the adjacent, relatively high pressure, atmosphere. By the connection of the aforescribed collector bag to a sub-atmospheric or vacuum source, the low pressure source accomplishes two functions that are new and quite advantageous in devices of this type. First the low pressure produced within the collector bag causes the relatively high atmospheric pressure outside of the bag to hold the bag in sealing engagement with the patient's body so that any urine or other liquid matter discharged into the collector bag cannot leak out of the bag. Second, the low pressure suction source will cause immediate withdrawal of the liquid from the collector bag after the urinary act so that the liquid may be readily discharged into an accumulator jar, reservoir, discharge trap, or the like. This prevents any bulkiness being developed within the bag during use. Quick removal of the urine deposited in the bag will also prevent skin irritation. The immediate removal of the urine from the collector bag will also prevent the development of odors. Immediate removal of the urine also keeps the bag dry on the inside so that in the event a leak should accidentally develop due to activity on the part of the patient, then there will be no spillage of urine on to the adjacent bedding, undergarments, or the like. The dual function of the sub-atmospheric pressure source that is attached to the urine collector bag is thought to be new and novel in devices of the general type herein described.

Looking at the drawings, Fig. 1 shows one form of this invention wherein the collector bag 10 is connected by a conduit 11a, 11b to a subatmospheric suction pump P. Intermediate the adjacent ends of the conduit sections 11a, 11b, there is an accumulator jar or reservoir

13. In the instance shown the jar 13 is in the form of a pitcher having a handle 14, a pouring spout 15 that is closed off by a removable cap 16, and a removable cover 17 to seal off the interior of the pitcher. Conduit section 11a has one end connected to the interior of the accumulator 13 through a sealproof grommet 18. The other end of conduit section 11a is sealingly connected to the collector bag 11 as will be presently explained. One end of the conduit section 11b is likewise connected to the interior of the pitcher 13 by means of a sealproof grommet 19. The other end of conduit section 11b is connected to the suction pump P.

Pump P is preferably electric motor driven by a motor M. The motor M may be of variable speed control, or at least have two speeds, so that one sub-atmospheric pressure can be produced at a relatively low motor speed to take care of the patient when he is normally resting in bed in a relaxed condition and a second higher speed to produce a greater sub-atmospheric pressure to take care of the patient when he might be more active than normally. The motor M is shown with a control lead 21 having a control switch 22 with two contacts F and S to denote "fast" or "slow" speed depending on what degree of sub-atmospheric pressure is desired. For normal requirements pump speeds that will produce sub-atmospheric pressures of from 2 to 8 inches of mercury are satisfactory.

The pump P can be any form of suction pump such as a vane, slipper, piston or rotor type. It is necessary that the pump P be quiet and of a type that does not require oil or grease type lubrication. There is a danger of fumes or impurities being discharged into the room of the patient if oil or grease lubricants are required for either the pump P or the motor M. Pump P is provided with an adjustable suction control valve such that the maximum sub-atmospheric pressure to be developed in the collector bag 10 can be readily controlled. Any type of limit valve V may be used. The type shown is just by way of example and is not indicative of any preferred type.

The collector bag 10, which involves the nucleus of this invention, is essentially a pair of waterproof pants formed from a sheet of elastic material. These pants 10 have zipper fasteners 31 along each side seam so that the pants-like unit can be opened up into substantially a flat sheet for easy insertion beneath a patient. Any type of fastening means 31 could be used. Alternatively, the collector bag unit 10 could be a single piece or integral unit that would be applied to the patient as a conventional pair of underpants would be put on. The leg openings 32 in collector bag 10 have enlarged roll edges 33 so that they may effectively seal against the patient's legs when the interior of the collector bag is subject to a sub-atmospheric pressure. The upper edge 34 of the collector bag 10 is also formed with an enlarged roll edge so that it may effectively seal against the patient's body. The actual crotch portion 35 of the collector bag 10 is outlined by a series of inwardly projecting ribs 36. These ribs 36 prevent complete collapse of the collector bag 10 when it is subjected to a sub-atmospheric pressure. These ribs 36 also provide effective sealing lips to define the area within which the urine will be collected. The spaced apart ribs 36 provide multiple lip seals that prevent leakage of any urine from within the bag 10. It will be noted that the lip seals 36 are of such a shape that they restrict the urine collection area to a relatively small part of the pants-like collector bag 10. The portions of the bag 10 above the ribs 36 can be perforated as at 39 to permit air to readily circulate and thus prevent perspiration formation. The lower part 38 of the crotch portion 35 of the collector bag 10 is shaped to provide a trough-like channel to collect the urine discharged into the bag. Trough 38 is connected to the conduit 11a so that any urine collected in trough 38 can be readily passed into the accumulator jar 13. It has

been found that the very thin, flexible, rubber-like materials and synthetic rubbers and waterproof plastic materials that are being used for certain undergarments at the present time are also quite adaptable for formation of the collector bag 10. It will also be noted from the drawings that the walls of the trough 38 may be relatively thick to resist collapse when the conduit 11a is connected to a sub-atmospheric pressure source. Trough 38 is not a stiff section because it must be flexible enough to conform to body crotch portion.

Fig. 6 shows another embodiment of this invention that is quite inexpensive and quite satisfactory if a water outlet is conveniently located with respect to the patient. In this form of the invention the same type of collector bag 10 is adapted to be applied to the patient and the conduit 11a connects the drain trough 38 of the collector bag 10 to a water ejector fitting 41. Ejector fitting 41 is essentially nothing other than a venturi such that when water from outlet 42 passes through conduit 11c and 20 through the ejector venturi 41 into the discharge conduit 11d a sub-atmospheric pressure will be developed in the conduit 11a and in the interior of the collector bag 10. As with the other form of the invention shown in Figs. 1-5, the sub-atmospheric pressure in conduit 11a is applied to the interior of the collector bag 10 to effect a leakproof seal between the bag 10 and the body of the patient using the device.

Furthermore, the sub-atmospheric pressure in conduit 11a produces a suction that withdraws the liquid collected in bag trough 38 and deposits it in the discharge conduit 11d so that it may be conducted to a discharge trap or the like.

From the foregoing description it is clear that there has been provided a new and improved type of urination control device that is of a simple, inexpensive, form and one that is equally applicable to a male or female person. The design of the collector bag unit of this device is such that it is easy to apply, leakproof, comfortable to wear and conducive to uninterrupted rest. The use of 40 a two-speed motor M to drive the suction pump P and the incorporation of a pressure limit valve V in the suction system are other features that insure the efficient operation of this device without any discomfort to the user.

I claim:

45 1. In a urination control device a urine collector bag comprising a pants-like garment of water-proof material having a collector trough formed in the crotch portion thereof, a discharge conduit connected to said collector trough, and inwardly projecting ribs on the interior surface of said garment surrounding said crotch portion and adapted to seal off said crotch portion against the adjacent portions of a human body when the interior of said garment is subjected to a sub-atmospheric pressure while the bag is applied to the crotch portion of a human body, a motor driven source of sub-atmospheric pressure connected to said conduit means, and a pressure control valve connected to said pressure source to limit the pressure applied to said collector bag.

60 2. In a urination control device a urine collector bag comprising a pants-like garment of water-proof material having a collector trough formed in the crotch portion thereof, a discharge conduit connected to said collector trough, and inwardly projecting ribs on the interior surface of said garment surrounding said crotch portion and adapted to seal off said crotch portion against the adjacent portions of a human body when the interior of said garment is subjected to a sub-atmospheric pressure while the bag is applied to the crotch portion of a human body, a motor driven source of sub-atmospheric pressure connected to said conduit means, and a pressure control valve connected to said pressure source to limit the pressure applied to said collector bag.

65 3. A urination control device for use by a human being

comprising a fluid collector bag to be worn by a patient in the form of a liquid-proof, pants-like, garment having a trough-like crotch portion that is surrounded by internally disposed sealing rib means extending continuously around said crotch portion, a fluid drain conduit connected to said crotch portion, a motor driven suction pump connected to said conduit to provide a sub-atmospheric pressure within the collector bag to cause the continuous, internally ribbed, portions of the bag to be drawn into sealing engagement with the body of the patient, said pump also functioning to withdraw any fluid deposited within the bag crotch portion, and an accumulator tank connected to said fluid drain conduit to receive the fluid withdrawn from the collector bag by said pump.
